[**] Term: 14 Years

[57] CLAIM

[21] Appl. No.: 65,565

The ornamental design for a spike to facilitate insertion of a
plant watering spike, as shown.

[22] Filed: Jan. 29, 1997

DESCRIPTION

Related U.S. Application Data

[63] Continuation-in-part of Ser. No. 594,346, Jan. 30, 1996, Pat.
No. 5,692,338.

FIG. 1 is a top plan view of a spike to facilitate insertion of
a plant watering spike, showing my new design;
FIG. 2 is a front elevational view thereof;
FIG. 3 is a right-side elevational view thereof;
FIG. 4 is a left-side elevational view thereof;
FIG. 5 is a rear elevational view thereof;
FIG. 6 is a bottom view thereof;

[51] LOC (6) Cl. 08-01
[52] U.S. Cl. D8/1
[58] Field of Search D8/1; 47/48.5,
47/44, 79, 80

FIG. 7 is a cross-sectional view shown along lines 7—7;
FIG. 8 is a first perspective view thereof;
FIG. 9 is a second perspective view thereof;
FIG. 10 is a top plan view of a second embodiment of a spike
to facilitate insertion of a plant watering spike;
FIG. 11 is a front elevational view, the rear, left and right
sides being identical thereto;
FIG. 12 is a bottom view thereof; and,
FIG. 13 is a cross-sectional view shown along lines 13—13
in FIG. 10.

The structure indicated in the drawing figures by broken
lines is not part of the design sought to be patented in this
application.
